(57) **CLAIM**

The ornamental design for a trim and frame portion of a light fixture, as shown and described.

DESCRIPTION

FIG. 1 is a bottom perspective view of a trim and frame portion of a light fixture showing my new design; FIG. 2 is a side view, the opposite side view being a mirror image thereof;

FIG. 3 is a bottom view thereof; and,

FIG. 4 is an end view, the opposite end being a mirror image thereof.

Where certain features are shown only on one side of the light fixture, the features are the same as the corresponding features on the other side of the light fixture in view of the symmetrical nature of the claimed design.

The broken lines shown on the drawings are for illustrative purposes only and form no part of the claimed design.
